[57] CLAIM

The ornamental design for a therapeutic fluid pump, as shown and described.

DESCRIPTION

FIG. 1 is a top perspective view of a therapeutic fluid pump showing our design, the broken line showing the conduit is for illustrative purposes only and forms no part of the claimed design;
FIG. 2 is a side elevational view thereof;
FIG. 3 is a top plan view thereof;
FIG. 4 is a bottom plan view thereof;
FIG. 5 is a front elevational view thereof; and,
FIG. 6 is a back elevational view thereof.
